CONTROL MECHANISM FOR SEWING MACHINES

Filed Jan. 19, 1927

UNITED STATES PATENT OFFICE

DAVID BESWICK, OF BROOKLYN, NEW YORK

CONTROL MECHANISM FOR SEWING MACHINES

Application filed January 19, 1927. Serial No. 162,138.

This invention relates to control mechanisms for sewing machines and more particularly to knee operated devices for controlling the speed of electrically driven sewing machines.

5 It is a general object of the present invention to provide a novel and improved form of knee control mechanism for sewing machines.

10 More particularly it is an object of the present invention to provide a novel mechanism adapted to clamp a portable sewing machine to a table or a like supporting surface and to provide means whereby a control button or lever on the machine may be actuated by the knee.

15 A further object of the invention consists in the provision of a device adapted to interlock with the base of a sewing machine and having a lever system adapted to cooperate at one end with a control button on the machine base and at the other end to be actuated by the knee, means being provided to attach the mechanism to a table or other supporting 20 means whereby the machine is prevented 25 from movement by pressure on the actuating device.

Other and further objects of the invention will be more apparent to those skilled in the 30 art upon a careful consideration of the accompanying drawings and following specification, wherein is disclosed a single exemplary embodiment of the present invention with the understanding, however, that such 35 changes may be made therein as fall within the scope of the appended claims without departing from the spirit of the invention.

In said drawings:

Figure 1 is a side elevation of a portion of the 40 a table top showing the operating mechanism of the present invention attached thereto, a portion of a portable sewing machine being disclosed in elevation therein;

Figure 2 is an end elevation of the parts 45 shown in Figure 1;

Figure 3 is a partial plan view thereof; and

Figure 4 is a vertical central section thru the operating mechanism taken on line 4-4 50 of Figure 2.

In the applicant's copending application Serial No. 19,726, filed March 31, 1926, for electric driven portable sewing machine, is disclosed a portable sewing machine having a base which is hollow and encloses the rheostat for controlling the speed of the motor used for driving the machine. An operating button projects thru the front edge of the base where it may be conveniently manipulated by the thumb while sewing. There is also disclosed in that application mechanism whereby the button may be operated by a foot treadle. The present invention contemplates the provision of means for operating such a control button by the knee.

55 Referring to the drawing there is disclosed at 10 the base of a sewing machine which is hollow and contains a rheostat (not shown) adapted to be operated to regulate the speed of the driving motor 11 by means of the control button 12 projecting thru the front face or edge 13 of the base. The button is adapted for reciprocation to control the speed of the motor which drives the fly wheel 14 by means of an internal friction disk, not shown.

70 The sewing machine, including the motor which is mounted on an extension of the base 10, is shown as supported on a table or other suitable support such as 15. The knee control mechanism forming the object of the 75 present invention, is indicated generally by the reference character 16 and is adapted to cooperate with the control button 12. It is clamped over the front edge of the table 15 and has a plate 17 which may be adjustably 80 positioned in respect to the floor in order that the operator's knee may conveniently be placed beneath the plate so that by lifting the heel the knee may be raised to raise the plate and, by means of the mechanism to be later 85 described, regulate the position of the control button 12.

Since the pressure on the button is in a direction parallel to the surface of the table it is seen that the sewing machine, being quite 90 light, must be secured against movement away from the edge of the table. This is secured by clamping the machine to the table by means on the knee control mechanism.

95 The base of the machine is provided with 100

two forwardly projecting bosses 18 which lie with their bottoms against the table surface and are perforated vertically as shown at 19. A casting 20 of substantial T-shape in plan has the head 21 thereof provided with the wings 22 adapted to rest on top of the bosses 19. Each wing is provided with a depending pin 23 adapted to pass into the corresponding opening 19 in the boss. These pins may conveniently be the lower ends of screws passed thru the wings. The tail of the T is enlarged as at 24 to provide a circular portion perforated vertically as at 25 and adapted to receive therein the tube 26. This tube may have a pressed fit into the portion 24 so that its end is just flush with the top of this portion. The lower part of the tube 26 is externally threaded as shown at 27.

A lower clamp member 28 is provided with 20 the sleeve 29 adapted to have a loose sliding fit over the tube 26. A suitably splined connection 30 prevents rotation of the sleeve. On the end of the member 28 is a clamping pad 31 directly beneath the head 21 of the T. 25 A wing nut 32 is threaded onto the tube 26 and is adapted to engage the bottom of the sleeve 29 so that the pad 31 can be clamped against the bottom surface of the table, drawing down the wings 22 onto the bosses 18 and 30 securely holding the machine base to the table in order that it may not slide when the button is pressed. Between the wings 22 the head portion 21 extends substantially down to the table top as shown at 33 in order to prevent 35 clamping the machine so tightly that the bosses are drawn into the material of the table top and the rear of the machine thus elevated.

Pivoted to the screw 34, the lower end of which forms one of the pins 23, is the button 40 controlling lever 35 which may conveniently have the tapered shape shown in Figure 3. It extends from the screw 34 over the end of the button 12 as best shown in Figures 1 and 3. It will be seen that movement of the lever 45 toward the machine base will cause the button to be pressed inwardly. Such movement of the lever is effected by the cranked lever 36 pivoted at 37 in a slot in the part 21, the end of the cranked lever partially fitting within 50 the slot. The curved face 38 of this lever engages against the front edge of the lever 35. It will be seen that raising the outer end 39 of the lever 36 will cause the inclined face 38 to press against the front face of the lever 35 and thus cause inward movement of 55 the button 12. The outer end 39 of the cranked lever is adapted to be raised by engagement with the head 40 of the control tube 41 which fits with a snug sliding fit 60 within the tube 26, the head resting on the end of the tube 26 and the enlargement 24. The tube 41 extends a considerable distance below the end of the tube 26 as best shown in Figure 65 1 and is surrounded by an open coiled spring 67 42 which bears at its upper end against the

lower end of the tube 26 and at its lower end against the ferrule 43 secured to the tube 41 in any suitable manner.

The knee plate 17 is attached to a rod 44 which has a sliding fit within the tube 41. It may be secured in any desired adjusted position according to the height of the operator's knee from the floor by means of the thumb screw 45 threaded thru the ferrule 43 and the tube 41 and having its end bearing against the rod 44. It will thus be seen from the constructions described that an upward movement of the knee plate 17 will impart a similar movement to the head 40 of the tube 41 which will lift the end 39 of the cranked lever 36, which will cause the inclined face 38 of this lever to bear against the front edge of the lever 35 causing the end of the same to move inwardly and press the button 12 in the same direction. The rheostat is so arranged that this inward movement of the button gradually eliminates resistance from the motor circuit.

It will be seen that the knee control mechanism performs two functions, i. e., it first 90 securely clamps and positions the sewing machine in relation to the edge of the table and holds it against movement and second, it provides means whereby motion of the knee in a vertical direction may be readily controlled, transmitted and reduced in quantity to the button 12 whereby a minute control of the speed of the motor may be obtained. The device is readily attached and detached by the mere actuation of the wing nut 32 95 and, being small in size, is easily portable and can be clamped in the carrying case of the machine. The most valuable features of the device is that it does not require any special form of rheostat to be designed for 100 it, it being adaptable to control the speed of any machine having a button which is intended for manual control at times. The operating device is self contained, having its own return spring. It is adjustable in height 105 from the floor to suit all ordinary sized persons and its operation in practice has been 110 found extremely satisfactory.

Having thus described the invention, what is claimed as new and desired to be secured 115 by Letters Patent is:

1. The combination with a sewing machine having a push button projecting therefrom, and a support for said machine of an operating mechanism for said push button 120 clamped to said machine, and to said support.

2. The combination with a sewing machine having a push button projecting therefrom, and a separate support for said machine, of 125 an operating mechanism for said push button and means on said mechanism to clamp said machine to said support.

3. The combination with a portable sewing machine having a horizontally movable 130

push button projecting therefrom, and a separate horizontal support for said machine, of means for converting vertical motion to horizontal motion to operate said push button, said means being secured to said support.

gaged by said first lever for the purpose described.

In testimony whereof I hereunto affix my signature.

DAVID BESWICK.

70

4. The combination with a portable sewing machine having a horizontally movable push button projecting therefrom, and a separate horizontal support for said machine, of means for converting vertical motion to horizontal motion to operate said push button, said means being removably clamped to said support.

75

5. The combination with a sewing machine having a horizontally movable push button projecting from the base thereof, and a horizontal support on which said machine rests, of means for converting vertical motion to horizontal motion to operate said push button, said means being interconnected with said machine and said support to prevent relative horizontal movement.

80

6. In combination with a sewing machine having a base with a button projecting therefrom, of a clamp adapted to secure said base to a support, a member slideable in said clamp and adapted to be moved by the knee of an operator and means whereby the movement of said member is transmitted to said button.

85

7. In combination with a sewing machine having a base with a button projecting therefrom, of a clamp adapted to secure said base to a support, a member slideable in said clamp and adapted to be moved by the knee of an operator, a lever pivoted to said clamp and having one end in engagement with said button and means connecting said lever and member for movement in unison.

90

8. In a knee control for sewing machines, in combination, a member adapted to be supported adjacent a machine, a tube depending therefrom, a second tube slideable in said first tube and having an end above said member, a knee plate associated with said second tube, a cranked lever having one end pivoted to said member and the other end resting on said end, a second lever pivoted to said member in a plane at right angles to that of the first lever, a portion of said first lever being adapted to bear on said second lever for the purpose described.

95

9. In a knee control for sewing machines, in combination, a member adapted to interlock with the base of a sewing machine, a tube depending therefrom, a clamp arm slideable on said tube, a second tube slideable within said first tube, a knee plate secured to said second tube, an end on said second tube above said member, a cranked lever having one end pivoted to said member and the other end resting on said end and a second lever pivoted to said member and adapted to be en-
